ELECTRIC SHAVER

Ralph J. Julian, Spokane, Wash.

Application July 5, 1949, Serial No. 103,010

2 Claims. (Cl. 30—43)

1

This invention relates to an electric shaver and more particularly to a comb for such a shaver, it being one object of the invention to provide a comb so constructed and so mounted that when the shaver or razor is in use the comb will have oscillating movement imparted to it and whiskers caused to pass through the comb and into position for the blade of the razor to cut the whiskers. It will thus not be necessary to move the razor back and forth across a person's skin several times in order to cause the whiskers to be moved through openings in the comb and a shaving operation may be quickly performed and without irritating the skin.

Another object of the invention is to provide a comb which may be tiltably mounted for movement upon a shaft from which the blade is supported and operated, thus reducing the number of parts and simplifying the construction.

Another object of the invention is to provide an electric razor wherein oscillating movement is imparted to the comb by a yoke which is mounted in a cam groove formed about the fly wheel of the motor for the razor.

Another object of the invention is to so construct the comb and its operating mechanism that it may be incorporated in an electric razor of conventional construction.

The invention is illustrated in the accompanying drawings wherein:

Fig. 1 is a plan view of the improved razor.

Fig. 2 is a view showing the improved razor partially in plan and partially in section.

Fig. 3 is a transverse sectional view taken along the line 3—3 of Figure 1.

Fig. 4 is a view in cross section taken at right angles to Figure 3.

Fig. 5 is a perspective view of the comb.

This improved electric shaver or razor has a casing 1 which is formed of plastic, or other suitable material, and is open at its front end. A motor 2 is mounted in the casing and is supplied with current by means of the usual cord 3. The shaft 4 of the motor projects forwardly and at its front end carries a fly wheel 5 about which a groove 6 serving as a cam is formed. A pin 7 projects forwardly from the fly wheel in eccentric relation thereto and engages in a groove 8 formed in a rim 9 extending longitudinally of a sleeve 10 which is rotatably mounted about a rocker shaft 11 journaled in bearing arms 12. The pin 7 imparts rocking moving motion to the sleeve 10 and this causes an arm 13 projecting from the sleeve to have oscillating movement and with it moves a blade 14 which is arcuate in cross section. Caps

2

15 at opposite sides of the front end of the casing are pivotally mounted in bearing brackets 16 and are normally held in a closed position by springs 17. When the caps are swung outwardly and downwardly to an opened position access may be had to the mechanism housed in the front end of the casing.

The comb 18 with which the blade 14 cooperates consists of a perforated metal plate 19 which is 10 arcuate in cross section and is secured to side bars 20 of a similarly shaped frame 21. This frame has arcuate end bars 22 and each end bar is formed with a longitudinally extending groove 23 so that ends of the frame may be overlapped by marginal edges of the caps 15. Side edge portions of the frame and the perforated metal plate 19 are overlapped by lips 24 of the casing and therefore during use of the shaver the comb may have transverse oscillating or vibrating movement. Tongues 20 or ears 25 project from the end bars of the frame and are secured to end plates 26 which are tapered downwardly and have hubs 27 at their lower ends. The hubs project inwardly from the end plates and are rotatably mounted about the shaft 11 and adjacent one side of the comb each plate carries a screw 28. About the screws, which serve as pivot pins engage eyes 29 at upper ends of the upstanding arms 30 of a yoke 31 which extends longitudinally of the comb in downwardly spaced relation thereto, the arms being slidably mounted in guides 32 carried by the upper portion of the casing. A lug 33 projects from the yoke midway the length thereof and is engaged in the cam groove 6 of the fly wheel 5 and as the fly wheel 35 rotates reciprocating movement is imparted to the yoke so that its arms slide longitudinally through the guides and impart oscillating movement to the comb. The comb moves in a direction opposite to that of the blade and whiskers which pass through the perforations of the plate 19 of the comb will be easily and quickly cut by the blade. Therefore during a shaving operation one movement across a portion of a person's face will cause the whiskers to be cut and it is not necessary to go over the face several times in order to obtain a close and clean shave.

Having thus described the invention, what is claimed is:

1. In a shaver, a casing having transversely spaced bearing arms integral with its front end and a recess between the arms, a motor in said casing having a forwardly projecting shaft, a fly wheel carried by the front end of said shaft and disposed in said recess, said fly wheel being 50 formed with a circumferentially extending cam

groove, a shaft supported between said bearing arms, and extending transversely of the body forwardly of the recess, a pin projecting forwardly from said fly wheel eccentric thereto, a blade holder mounted about said shaft for oscillating movement and carrying a transversely arcuate blade, caps at opposite sides of the front end of said casing hinged to the casing for tilting movement to opened and closed positions and yieldably held closed, a comb having a transversely semicircular frame and a plate of perforated metal mounted upon the frame externally thereof and conforming to its transverse curvature, and plates for said frame overlapped by edge portions of the caps when closed, said end plates being tapered rearwardly and at their rear ends carrying hubs loosely mounted about the shaft at opposite ends of the blade carrier, bearing brackets carried by said casing, a U-shaped yoke having a bridge extending across the peripheral edge face of the fly wheel and arms slidably passing through said bearing brackets and pivoted to the end plates in eccentric relation thereto, and a finger projecting from the bridge of said yoke midway the length thereof and engaged in the cam slot whereby reciprocating movement will be imparted to the yoke and the comb oscillated about the shaft and moved in a direction opposite to movement of the blade during rotation of the motor shaft and the fly wheel.

2. In a shaver, a casing, bearing arms at the front end of said casing, a shaft supported between said arms, a motor in said casing having a forwardly extending shaft and a fly wheel carried thereby, a blade holder carried by said shaft and carrying a blade at its front, a comb having a transversely arcuate frame and plates at ends thereof loosely mounted about said shaft and mounting the comb for oscillating movement, a perforated plate carried by said frame in cooperating relation to the blade, guides carried by the bearing arms of said casing, a yoke having a bridge extending transversely of the shaft and arms slideable longitudinally through the guides and pivoted to the end plates, and a lug projecting from the bridge and engaged in a cam groove formed about the fly wheel for reciprocating the yoke and imparting oscillating movement to the comb during rotation of the fly wheel.
